LADY'S STOCKING

Joe T. Welch, Burlington, N. C., assignor to Burlington Mills Corporation, Greensboro, N. C., a corporation of Delaware

Application July 6, 1950, Serial No. 10,986

Term of patent 14 years

(Cl. D47—7)

To all whom it may concern:

Be it known that I, Joe T. Welch, a citizen of the United States, and a resident of Burlington, in the county of Alamance, State of North Carolina, have invented a new, original, and ornamental Design for a Lady's Stocking, of which the following is a specification, reference being had to the accompanying drawing, forming part thereof.

In the drawing—

I claim:

The ornamental design for a lady's stocking, as shown.

JOE T. WELCH.
